UNITED STATES PATENT OFFICE.

EARNEST R. FERRARI, OF NORTH BEND, OREGON.

FINGER RING.

Application filed November 14, 1923. Serial No. 674,740.

The object of my said invention is the provision of a finger ring equipped for convenient use as a match striker and nail filer and this without materially increasing the cost of production of the ring and without detracting from the ornamental character of the ring. 5

To the attainment of the foregoing, the invention consists in the improvement as 10 hereinafter described and definitely claimed.

In the accompanying drawings, forming part of this specification:—

Figure 1 is an edge elevation of my novel ring.

15 Figure 2 is a side elevation of the same.

Figure 3 is a view showing in plan the striking surface of the ring.

20 Figures 4 and 5 are views of a modification in which the filing or striking surface of the ring is formed by a stone or by a tungsten steel plate or other metallic plate carried by the metallic or alloy portion of the ring.

25 Similar numerals designate corresponding parts in Figures 1 to 3 to which reference will first be made.

The major portion of my novel ring is 30 formed of any appropriate metal or alloy compatible with its purpose and comprises a finger receiving annulus 1 which in practice is made in various sizes to receive fingers of various sizes in cross-section. At the outer side of the annulus 1 the ring is provided with a thickened portion 2 integral with the annulus 1 and extending through about $\frac{1}{3}$ of the circumference thereof and said thickened portion having its side walls concaved as shown in Figure 2 to provide spaced projections 3, and in its 35 outer side and extending between the apices of the projections 3 is a filing or striking surface 4, in a corrugated manner preferably produced by roughening the surface 4, as illustrated. It will be noted that the surface 4 is almost if not quite as long as the 40 diameter of the annulus 1, this being advantageous inasmuch as it tends to prevent turning of the ring about the finger incident to the striking of a match on the surface 4 or the use of the said surface 4 for 45 filing a finger nail on the other hand of the wearer. It will also be noted that the advantage indicated is attained by the making of the surface 4 concave in the direction of

its length which is the preferred embodiment.

In Figures 4 and 5, I illustrate a modification of my invention in which the annulus 1^a is equipped to carry in fixed relation an inlaid element 5 which element 5 is provided with a nail-filing or scratching surface 4^a similar to and for the same purpose as the scratching surface 4 described with reference to Figures 1 to 3.

The element 5 may be a stone without affecting my invention, though I prefer to form it of a tungsten steel plate or other metal plate and to provide it with a roughened or file-like surface. The plate of tungsten steel is preferred because of its bright or shining quality which enhances the ornamental appearance of the ring. 65

Notwithstanding my improvement adds materially to the range of utility of the finger ring, it will be appreciated that the improvement does not materially increase the production cost of the ring; and it will also be noted that the practical purpose or purposes to which the ring may be put does not diminish in any measure the ornamental 75 character of the ring.

I have entered into a detailed description of the construction and relative arrangement of the parts embraced in the present and preferred embodiments of my invention in order to impart a full, clear and exact understanding of the said embodiments. I do not desire, however, to be understood as confining myself to the specific construction and relative arrangement of parts inasmuch as in the future practice of the invention various changes and modifications may be made such as fall within the scope of my invention as defined in my appended claims. 85 90 95

Having described my invention, what I claim and desire to secure by Letters-Patent, is:—

1. A finger ring comprising an annulus, and an element carried by and fixed to the annulus and having at one side of the annulus a transversely roughened surface for nail filing or match striking purposes extending throughout a considerable portion of the circumference of the annulus and dished in the direction of its length; the said annulus being provided with spaced projections and a thickened portion between

said projections in which said element is held.

2. A finger ring comprising an annulus, a thickened portion formed thereon and extending through about one-third of its circumference, said thickened portion having its side walls concaved to provide oppositely disposed projections and being dished in

the direction of its length reversely to the curvature of its annulus, and said dished portion being corrugated for the purpose specified.

In testimony whereof I affix my signature.

EARNEST R. FERRARI.
